POWER DRIVEN RAZOR

Arthur E. Jensen, Anaheim, Calif.

Application April 13, 1937, Serial No. 136,597

9 Claims. (Cl. 30—43)

My invention relates to power driven razors and has particular reference to a machine adapted to clip or shear hair close to the skin, adapting the same to be used for shaving purposes.

5 In adapting hair clipping or shearing machines to be used as razors, considerable difficulty has been encountered in locating the shearing edges of the machine sufficiently close to the skin to effectively cut the hair therefrom at the 10 skin surface without allowing the skin to be endangered by the movable shearing blades.

In my copending application Serial No. 105,251, filed October 12, 1936, patented February 7, 1939, No. 2,146,298, I disclose a hair clipping or shearing machine in which a relatively thin stationary blade is employed in cooperation with a relatively heavy shearing blade reciprocating relative to the stationary blade for the purpose of presenting the actual shearing edges of the two 20 blades extremely close to the surface of the skin engaged by the machine. In said copending application I disclosed a stationary blade member which included a shearing edge from which extended a plurality of guard ribs, the guard ribs 25 acting to support and lend rigidity to the blade whereby the blade could be made extremely thin and in which a movable blade reciprocated longitudinally of the ribs to approach the stationary blade and shear the hair therebetween along the 30 principle of shearing employed in lawn mowers.

The present invention constitutes an improvement over the construction shown in the said copending application and has for its principal object the production of a razor employing a 35 movable blade oscillating longitudinally toward and away from a stationary blade and in which the length of the movable blade between its pivot point and its cutting edge is such that the arc through which the movable blade swings is substantially normal to the direction in which the 40 hair extends from the skin.

Another object of my invention is to provide a razor of the character set forth in the preceding paragraph wherein by employing a relatively 45 great length of blade between the pivot point and the cutting edge a greater length of movement of the edge of the blade in substantial parallelism with the skin may be accomplished.

Another object of my invention is to provide a 50 machine of the character set forth in which power may be readily transmitted to the movable blade by direct connection between a power mechanism and the movable blade.

Another object of my invention is to provide 55 a machine of the character set forth wherein a

rotary motor may be employed for producing an oscillation of the movable blade and wherein an eccentric mounted directly upon the motor shaft may be employed to produce the oscillatory motion of the blade by direct connection therewith. 5

Another object of my invention is to provide a stationary blade and guard member wherein the guard ribs are presented to the skin surface having depressions therein permitting the skin to project closer to the path of movement of the 10 movable blade at one or more points along each of said ribs whereby the movement of the movable blade will be enabled to pick up hairs projecting from the skin and swing them into shearing relation between the stationary and movable 15 blades.

Other objects and advantages of my invention will be apparent from a study of the following specifications, read in connection with the accompanying drawings, wherein:

Fig. 1 is a vertical sectional view taken through a razor constructed in accordance with my invention, substantially along the median vertical plane thereof;

Fig. 2 is a plan view of the razor illustrated in 25 Fig. 1;

Fig. 3 is a vertical elevational view of the razor 30 illustrated in Fig. 1, showing the handle or case of the razor with the front portion thereof removed;

Fig. 4 is an enlarged sectional view of the razor 35 head shown in Fig. 1, illustrating the shape of the guard ribs and the movable and stationary blades;

Fig. 5 is a detail sectional view through the 40 guard ribs, stationary blade and movable blade taken along the line V—V of Fig. 4; and

Fig. 6 is a detailed sectional view taken along line VI—VI of Fig. 4.

Fig. 7 is a perspective view of the stationary 45 blade and guard members and the movable blade showing their relation with each other.

Referring to the drawings, I have illustrated in Figs. 1 and 2 the general construction of a 50 razor constructed in accordance with my invention which comprises a suitable handle member or case 1 which may be constructed in any of the conventional manners, such as by casting the same of Bakelite or similar molded material in two half sections, including a rear section 2 and a front section 3. The rear section 2 of the handle or case 1 may comprise a hollow shell adapted to receive and support suitable motive power means illustrated herein as comprising an electric motor 4. The motor 4 may be of any de- 55

sired construction though I prefer that the same shall include a pair of field poles 5 and 6, each adapted to receive a field energizing coil 7 and 8, respectively. I prefer to locate the field poles 5 and 6 at opposite ends of the casing section 2 to provide therebetween a relatively large space adapted to receive the armature 9 of the motor. The armature 9 is illustrated as being mounted upon an armature shaft 10 suitably supported at 10 either of its ends in bearing members 11 and 12, these bearing members being formed in any desired manner as by employing bosses extending from straps 13 and 14, one on each of the front and rear sides of the field pole members 5 and 15 6. The straps 13 and 14 may comprise the frame of the motor as by riveting the members 13 and 14 together by rivets 15 which extend through the laminations comprising the field poles 5 and 18 6. The extreme ends of the straps 13 and 14 20 may be bent outwardly to constitute lugs 16 and 17 by which the motor may be secured to the casing section 2 as by means of screws 18.

The motor shaft 10 may be provided with an eccentric bushing 19 pinned or otherwise rigidly 25 secured to the shaft 10, as indicated at 20, so that as the motor shaft 10 rotates the eccentric will be rotated thereby.

It will therefore be observed that the motor 4 may be completely assembled in the casing section 30 2 and the casing section 3 will therefore merely act as a cover for the motor 4.

For purposes of clarity of illustration herein, no make and break devices are illustrated on the motor though it will be understood by those 35 skilled in the art that to adapt this motor for operation on direct current suitable make and break switching apparatus such as that shown in the Schick Patent No. 2,064,038, December 15, 1936, may be employed, while when used on 40 alternating current the armature shaft 10 may be provided with an extension projecting through the casing section 3 to permit the same to be manually started.

By referring particularly to Fig. 1, it will be 45 observed that the casing section 2 has at its upper end a forwardly projecting shelf member 21 and that the upper surface 22 thereof is formed upon an angle which extends at a considerable angle to the horizontal, this shelf and 50 the upper surface thereof constituting a support for a head 23 which includes the shearing mechanism. The head 23 may be constructed of a relatively flat and relatively heavy plate 24, from the side edges of which, nearly the rear of the plate, extends a pair of bearing brackets 25 and 26, in which brackets is journaled a shaft 27 which in turn constitutes the pivot mounting of 55 a movable or oscillating blade 28. The blade 28 comprises a relatively flat plate of suitable metal, 60 the rear end of which rests against the flat face 29 on the shaft 27 and is secured to the shaft 27 as by means of a pair of screws 30. The movable blade 28 is provided upon its outer end with a plurality of fingers 31, the outer ends of these 65 fingers comprising the cutting edge 32 of the oscillating blade. Intermediate the cutting edge 32 and the shaft 27 I connect the power mechanism by which the blade 28 is oscillated. This power mechanism is illustrated as an eccentric 70 strap 33 surrounding the eccentric 19, the ends of the eccentric strap 33 being bent upwardly as indicated at 34 to provide ears through which a pin 35 may extend to couple a connecting rod 36 to the strap 33. The upper end of the connecting rod 36 is bent inwardly as indicated at 75

38 and is provided with an opening 38, through which extends the lower threaded end of a rod 39. The upper end of the rod 39 is preferably formed as a ball 40 which seats within a socket formed by a semi-spherical depression 41 in the blade 28 while the complementary half of the socket is formed by a semi-spherical member 42 secured to the upper surface of the blade 28 as by means of screws 43.

With the construction thus far described, it 10 will be apparent that rotation of the motor shaft 10 will be transmitted through the eccentric 19, connecting rod 36 and ball and socket joint 40-41-42 as an oscillatory movement of the blade 28 in a vertical direction as viewed in Fig. 1. 15

By reason of the fact that the pivot shaft 27 for the blade 28 is located at the rear end of the plate 24, the cutting blade 28 may have a length almost equal to the full length of the plate 24 and thus the arc 44 described by the cutting edge 20 32 of the blade 28 will be along a relatively great radius so that the arc 44 closely approaches a straight line.

It will be understood that the views of the 25 razor illustrated in Figs. 1, 2 and 3 thereof are considerably enlarged over the actual dimensions of the razor as it is manufactured for use. In actual construction the radius along which the cutting edge 32 moves is preferably from 1 inch to 1½ inches in length. It will also be observed 30 that the total stroke of the outer or cutting edge of the blade 28 will be relatively short, less than ¼ inch. By reason of this construction, the arc described by the oscillatory movement of the outer edge of the blade will be substantially along a straight line or, to state it more exactly, that section of the arc which is employed for engaging the hairs and shearing them constitutes a short 35 arc of relatively great radius.

It will thus be observed that as distinguished 40 from previous razor constructions the movable blade will swing throughout its entire stroke along the line which is substantially parallel to the skin surface, indicated in Fig. 1 at 45.

The movable blade 28 is adapted to cooperate 45 with a stationary shearing blade 46 which is formed upon and preferably integrally with a guard plate 47. The guard plate 47 is formed with a base 48, through which a plurality of 50 screws 49 may extend into an enlarged or thickened front edge 50 of the head plate 24. The guard plate 47 includes an edge rib 51 at each of its sides, between which is formed a plurality of slots 52 as by cutting or milling through the thickness of the guard plate 47, leaving a plurality of relatively thin guard ribs 53 extending from the base 48 to a strip of metal interconnecting the edge ribs 51, which strip of metal 55 constitutes the stationary shearing blade 46.

By referring particularly to Figs. 1 and 6, it 60 will be observed that the guard ribs 53 extend throughout the thickness of the guard plate 47, entering into the space between the fingers 31 of the movable blade 28 so that these guard ribs may be made of any desired depth to achieve 65 rigidity in the direction normal to the contact of the guard plate with the face and such ribs act as braces supporting the stationary blade 46 rigidly even though the ribs 53 may each be made relatively thin.

By reason of this construction the slots 52 into which the hairs may project are made relatively great without sacrifice of rigidity of the guard ribs 53 and without weakening the stationary blade member 46. Also by reason of this con- 70

struction the stationary blade member 46 may be made extremely thin, namely, a few 1000ths of an inch thick, so that the shearing contact between the cutting edge 32 of the oscillating blade 28 and the blade 46 may be located within a few 1000ths of an inch of the outer or skin-contacting surface of the guard ribs 53 and an extremely close cutting or clipping of the hairs to the skin may be accomplished. It will be noted that as the razor is drawn downwardly over the skin surface 45 any projecting hairs 54 will enter the spaces between the guard ribs 53 and when the oscillating blade 28 starts its movement toward the stationary blade 46 the cutting edge 32 of the blade 28 will pick up the hair and swing it toward the stationary blade 46 where it will be sheared.

It will be noted that the base 48 is undercut below the outer surface of the ribs 53, as indicated at 55, so that as the razor is drawn downwardly the hairs 54 will be substantially combed into the space between the ribs 53. In order to further assist in achieving a close clipping or cutting of the hairs, I prefer to provide depressions in the ribs 53, both at the rearward portion of the stroke of the oscillating blade 28 and at the forward portion of the stroke of the oscillating blade 28, as indicated respectively at 56 and 57, such depressions being readily formed as by grinding an arcuate curve across all of the ribs 53. A depression 56 is preferably formed along an arc of relatively great radius so that a considerable area of the skin will sink into this depression and thus present a greater length of hair to be picked up by the moving edge 32 of the blade 28. However, the arc of the depression 57 immediately in advance of the stationary blade 46 may be made along a shorter radius so as to provide a substantial shoulder 57 on the ribs 53, pressing the skin surface 45 inwardly and drawing it substantially taut immediately in advance of the approaching stationary blade 46.

By referring particularly to Fig. 2, it will be noted that the shaft 27 is provided with bearing ends 27a at each of its ends, which are received in the bearing brackets 25 and 26. By forming annular recesses 59 in the bearing ends of the shaft, these recesses may be packed with suitable lubricant for the shaft bearings.

In order to compensate for any wear which may occur between the bearing pins 27 and the brackets 25 and 26 which may tend to prevent accurate shearing contact between the blade 28 and the stationary blade 46, I provide a spring 60 secured to the head plate 24 as by means of screws 61, the spring 60 being bent upwardly to engage a ball 62 in a recess 63 formed approximately centrally of the rear of the shaft 27. The employment of the spring 60 and ball 62 will tend to move the oscillating blade 28 constantly toward the stationary blade 46 with a minimum of friction between the shaft and the spring.

With the construction herein described, it will be apparent that a simple motor and casing construction may be employed to oscillate the blade 28 with a minimum of moving parts to wear or become out of adjustment. Also it will be noted that by reason of threading the rod 38 at its connection with the connecting rod 36 the extreme forward position (that is, the extent of movement of the cutting edge 32 of the blade 28 past the cutting edge of the stationary blade 46) may be carefully regulated and suitable nuts 58 may be employed to fix the rod 38 in its adjusted position.

It will also be noted that by constructing the head 24 as a plate extending transversely across one end of the handle member 1, that is, substantially transversely to the longitudinal axis of the handle member 1, and mounting the stationary blade 46 and its guard plate at one end of the head plate and pivoting the movable blade 28 at the opposite end of the head plate, the surface of the stationary blade and guard plate is disposed in a plane substantially parallel to a plane drawn along the longitudinal axis of the handle member and the razor is adapted to be held comfortably with the casing 1 extending parallel, or substantially parallel, to the skin surface over which the razor is to be drawn, thus distinguishing my construction from previous types of razors wherein the skin-contacting surface was so disposed relative to the handle as to require the handle to extend at substantially right angles to the skin surface to be shaved.

By reason of the construction herein described, the cutting edge of the movable blade swings along a line which is substantially parallel to the skin surface, thus providing a greater effective length of stroke to the cutting edge to pick up hairs and straighten them out to a position normal to the skin surface prior to the shearing of the hair and thus the hair may be cut much closer to the skin surface.

It will be understood by those skilled in the art that the power supply to the motor may be introduced through a suitable plug connection 64 which may be received in a suitable socket 65 formed by the complementary halves 2 and 3 of the casing, terminal members 66 being provided in the casing 1 to engage the plug member 64.

While I have shown and described the preferred embodiment of my invention, I do not desire to be limited to any of the details of construction shown or described herein, except as defined in the appended claims.

I claim:

1. In a power driven razor, a handle member, a head plate secured at one end of said handle member and extending transversely to the longitudinal axis thereof, a stationary blade member comprising a plate having considerable surface area adapted to be drawn over a skin area to be shaved, means mounting said stationary blade member at one end of said head plate to dispose the surface of said stationary blade member in a plane substantially parallel to the longitudinal axis of said handle member, a stationary blade on said stationary blade member extending transversely across said surface, and a movable blade member comprising an elongated plate having a cutting edge disposed transversely across one end thereof, means pivoting the other end of said movable blade near the opposite end of said head plate whereby the arc described by said cutting edge will be about a radius substantially equal to the length of said head plate.

2. In a power driven razor, a head plate, a stationary blade member on one end of said head plate having a skin-contacting surface disposed in a plane substantially transverse to the surface of said head plate, an elongated movable blade member having one of its ends formed with cutters cooperating with said stationary blade member, and means pivoting the other end of said movable blade member near the opposite end of said head plate whereby the cutters may swing in an arc the radius of which is substantially equal to the distance between the said ends of said head plate, a handle member attached to said head plate.

plate, power means in said handle and means connecting said power means to said movable blade at a point intermediate the ends of said movable blade.

5. 3. In a power driven razor, a head plate, a stationary blade member on one end of said head plate having a skin-contacting surface disposed in a plane substantially transverse to the surface of said head plate, an elongated movable blade member having one of its ends formed with cutters cooperating with said stationary blade member, and means pivoting the other end of said movable blade member near the opposite end of said head plate whereby the cutters may swing in an arc the radius of which is substantially equal to the distance between the said ends of said head plate, an elongated handle member attached to said head plate, a motor in said handle having a rotating armature, and connecting means coupling the armature of said motor to said movable blade at a point intermediate the ends of said movable blade to translate the rotation of the armature as an oscillatory movement of said blade.

4. In a power driven razor, a head plate, a stationary blade member on one end of said head plate having a skin-contacting surface disposed in a plane substantially transverse to the surface of said head plate, an elongated movable blade member having one of its ends formed with cutters cooperating with said stationary blade member, and means pivoting the other end of said movable blade member near the opposite end of said head plate whereby the cutters may swing in an arc the radius of which is substantially equal to the distance between the said ends of said head plate, an elongated handle member attached to said head plate, a motor in said handle having a rotating armature, an eccentric on said armature, and a connecting rod coupling said eccentric to said movable blade to oscillate said blade as said armature rotates.

5. In a power driven razor, a head plate, a stationary blade member on one end of said head plate having a skin-contacting surface disposed in a plane substantially transverse to the surface of said head plate, an elongated movable blade member having one of its ends formed with cutters cooperating with said stationary blade member, and means pivoting the other end of said movable blade member near the opposite end of said head plate whereby the cutters may swing in an arc the radius of which is substantially equal to the distance between the said ends of said head plate, an elongated handle member having one of its ends adapted to mount said head plate, a motor in said handle having a rotatable armature disposed for rotation about an axis transverse to the longitudinal axis of said handle member, and an eccentric on said armature, and a connecting means coupling said eccentric to said movable blade, said connecting means extending through said head plate.

6. In a power driven razor, a head plate, a stationary blade member on one end of said head plate having a skin-contacting surface disposed in a plane substantially transverse to the surface of said head plate, an elongated movable blade member having one of its ends formed with cutters cooperating with said stationary

blade member, and means pivoting the other end of said movable blade member near the opposite end of said head plate whereby the cutters may swing in an arc the radius of which is substantially equal to the distance between the said ends of said head plate, a handle member attached to said head plate, power means in said handle member and connecting means coupling said power means to said movable blade, said connecting means including a rod having a ball thereon, and a ball socket formed upon said movable blade intermediate its ends for receiving said ball.

7. In a stationary blade member for a razor, a stationary blade adapted to be drawn transversely across a skin area to be shaved and having a surface adapted to slide over the skin surface, a plurality of spaced guard ribs extending from the edge of said blade in the direction of movement thereof over the skin, the outer edges of said ribs constituting a continuation of the surface of said blade, and a transverse depression in each of said rib edges immediately adjacent said blade whereby the skin is depressed toward said blade as said blade is drawn over the skin surface.

8. In a razor having a stationary blade and a movable blade cooperating together to produce a shearing action, a movable blade having a cutting edge adapted to be moved through a fixed path, a stationary blade extending transversely of said path and having an outer surface adapted to engage and slide over a skin surface to be shaved, a plurality of guard ribs extending from said stationary blade in the direction of movement of said stationary blade over said skin surface, the outer edges of said ribs constituting a continuation of said surface of said stationary blade, and extending parallel to the path described by said movable blade edge, and a transverse depression in each of said ribs immediately adjacent said stationary blade whereby the space defined between the edge surface of said ribs and the path of said movable blade edge is reduced to allow the skin to project closely to said movable blade edge immediately in advance of said stationary blade.

9. In a razor having a stationary blade and a movable blade cooperating together to produce a shearing action, a movable blade having a cutting edge adapted to be oscillated through a fixed arcuate path of predetermined length and curvature, a stationary blade having a surface adapted to engage and slide over the skin surface to be shaved and having an edge disposed toward and transversely of the path of said movable blade and near one end of said path, a plurality of guard ribs extending from said edge in the direction of the path of movement of said movable blade, the edges of said ribs constituting an arcuate continuation of the skin engaging surface of said stationary blade concentric with said path and of greater length than said path, and a pair of depressions in each of said ribs one adjacent and immediately in advance of the edge of said stationary blade and the other adjacent the opposite end of the path of movement of said movable blade.

ARTHUR E. JENSEN.
